CLAIM

The ornamental design for cosmetic container, as shown and described.

DESCRIPTION

FIG. 1 is a top plan view of a cosmetic container showing my new design;

FIG. 2 is a bottom plan view thereof;

FIG. 3 is a front elevational view thereof;

FIG. 4 is a rear elevational view thereof; and

FIG. 5 is a right side elevational view thereof. The undisclosed left side is a mirror image of the side shown.
